(57) **CLAIM**

The ornamental design for a foot switch console for use with a surgical microscope, as shown and described.

DESCRIPTION

FIG. 1 is a front end elevation view of the foot switch console according to an embodiment of our design;

FIG. 2 is a rear end elevation view of the foot switch console of FIG. 1;

FIG. 3 is a left side elevation view of the foot switch console of FIG. 1;

FIG. 4 is a right side elevation view of the foot switch console of FIG. 1;

FIG. 5 is a top plan view of the foot switch console of FIG. 1;

FIG. 6 is a bottom plan view of the foot switch console of FIG. 1;

FIG. 7 is a perspective view of the foot switch console of FIG. 1;

FIG. 8 is a front end elevation view of an alternate embodiment of the foot switch console of our design;

FIG. 9 is a rear end elevation view of the foot switch console of FIG. 8;

FIG. 10 is a left side elevation view of the foot switch console of FIG. 8;

FIG. 11 is a right side elevation view of the foot switch console of FIG. 8;

FIG. 12 is a top plan view of the foot switch console of FIG. 8;

FIG. 13 is a bottom plan view of the foot switch console of FIG. 8; and,

FIG. 14 is a perspective view of the foot switch console of FIG. 8.

The portion of the base of the foot switch console shown in broken lines forms no part of the claimed design.
